INVENTOR
Godfrey Wickberg

BY *William Nichols*
ATTORNEY

UNITED STATES PATENT OFFICE.

GODFREY WICKBERG, OF SEATTLE, WASHINGTON.

TOOTHBRAHSH.

Application filed May 21, 1919. Serial No. 298,721.

To all whom it may concern:

Be it known that I, GODFREY WICKBERG, a citizen of the United States, residing at Seattle, county of King, and State of Washington, have invented certain new and useful Improvements in Toothbrushes, of which the following is a specification.

This invention relates to tooth brushes and it has for a general object to provide a novel and improved tooth brush with which both the inner and outer surfaces of the teeth may be conveniently brushed.

The invention also has for an object to provide a tooth brush peculiarly adapted for brushing the inner surfaces of the teeth.

Other objects relate to the provision of improved means for mounting the brush members on a suitable handle.

For further comprehension of the invention and of the objects and advantages thereof, reference will be had to the following description and accompanying drawings, and to the appended claim in which the various novel features of the invention are more particularly set forth.

Figure 1 is an elevation illustrating an embodiment of my improvement;

Figure 2 is a view at right angles to Fig. 1; and

Figure 3 is a cross section taken on the line 7-7 of Figure 2.

In the construction as shown in the drawing, 25 indicates the handle which may be flat as shown and provided on opposite ends 35 and on opposite faces with longitudinal dovetail grooves 26 and 27, which taper inwardly as shown.

The groove 26 has inserted therein a strip 28 to which the bristles 29 are fixed in the usual manner. This strip 28 preferably corresponds in dimensions to the groove 26 so as to preserve the contour of the handle when in position.

The groove 27 receives a complementary tail 30 on a strip 31 on which is mounted by a pin 32 a convex base 12 carrying bristles 33.

It is believed that the manner of using my improved tooth brush will be apparent from the foregoing description. In using the brush for cleaning the inside of the teeth the handle will be inserted between the teeth and then moved forwardly to bring the brush into engagement therewith, the brush then

being moved along the teeth in engagement 55 with the inner surfaces of the latter.

It will be apparent from the above that either of the brush elements can be removed while the other is being used, thus providing two distinct brushes, one for brushing 60 the outside and one for brushing the inside of the teeth. Also that both brushes will fit the same end of the handle, permitting both brushes to be used alternately on one end if desired. Also that an individual brush for 65 use on either the outside or inside of the teeth is provided.

It is noted that the handle 25 has a tapering longitudinal recess 27 at the right hand end thereof, the brush 33—having its back 70 32' enlarged to form a means of attachment thereof—being mounted upon the brush support comprising a narrow body portion 30 which is inserted in the said recess and moves longitudinally therein when being detached therefrom, which brush support also has an end portion 31 formed with shoulders 75 flush with and extending beyond the handle.

I provide means to stop undue inward movement of the said body portion 30 comprising the tapering recess 27, and also means comprising the dovetail sides of the said recess to partially resist outward movement thereof and, with the co-operation of the said shoulders, to prevent lateral movement of the said body portion when the handle is moved sidewise.

Having thus described my invention and set forth the manner of its construction, what I claim as new, and desire to secure by 80 Letters Patent, is:—

In a device of the class described, a flattened handle having a longitudinally grooved recess at the end thereof which is dovetailed in cross section, a detachable 95 brush supporting member having a shallow body portion which is dovetailed to be frictionally inserted in the recess of the handle and longitudinally movable in the direction of the handle when being detached therefrom, and also having an outer end part formed with shoulders flush with the handle end, and a brush carried by said support, said shoulders forming means to stop undue inward movement of the brush support.

In testimony whereof I have affixed my signature.

GODFREY WICKBERG.
